(57) **CLAIM**

The ornamental design for a filter segment for removing particle matter, as shown and described.

DESCRIPTION

FIG. 1 is a perspective view of a first embodiment of a filter segment for removing particle matter illustrating our new design;

FIG. 2 is a front view thereof;

FIG. 3 is a top view thereof, the bottom view thereof being a mirror image;

FIG. 4 is a right view thereof, the left view thereof being a mirror image;

FIG. 5 is a rear view thereof;

FIG. 6 is a middle omitted cross-sectional view taken through line 6-6 of FIG. 2;

FIG. 7 is a perspective view of a second embodiment of a filter segment for removing particle matter illustrating our new design;

FIG. 8 is a front view thereof;

FIG. 9 is a top view thereof, the bottom view thereof being a mirror image;

FIG. 10 is a right view thereof, the left view thereof being a mirror image;

FIG. 11 is a rear view thereof; and,

FIG. 12 is a middle omitted cross-sectional view taken through line 12-12 of FIG. 8.

The broken lines in the drawings depict unclaimed subject matter only and form no part of the claimed design.

1 Claim, 18 Drawing Sheets
